(No Model.)

M. L. WILCOX.
SLEIGH.

No. 441,729.

Patented Dec. 2, 1890.

ATTEST,

J. S. Thomas

F. A. M. May

INVENTOR -

Melvin L. Wilcox.
By Jas. S. Thomas
Atty.

UNITED STATES PATENT OFFICE.

MELVIN L. WILCOX, OF BAY CITY, MICHIGAN.

SLEIGH.

SPECIFICATION forming part of Letters Patent No. 441,729, dated December 2, 1890.

Application filed December 16, 1889. Renewed September 25, 1890. Serial No. 366,070. (No model.)

To all whom it may concern:

Be it known that I, MELVIN L. WILCOX, a citizen of the United States, residing at Bay City, in the county of Bay and State of Michigan, have invented certain new and useful Improvements in Sleighs; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to improvements in sleighs, and it pertains more especially to hand-sleighs; and the invention consists in devices for carrying wheels or rollers to be attached to an ordinary sleigh, so that the sleigh may be supported upon the said wheels or rollers or upon the runners, as desired.

The invention also consists in the combination and arrangement of the several parts and devices which are used in the construction of the improvement, which will be definitely explained hereinafter, and pointed out in the claims of this specification.

The objects of this invention are to provide devices for attaching rollers or wheels to a sleigh, so that the sleigh may be supported by the wheels or not, as desired.

Another object is to construct and arrange devices for attaching wheels to a sleigh, whereby the wheels may be easily and quickly placed in position for supporting the sleigh or withdrawn from such position and retained, so that the sleigh may be used in the ordinary way.

I illustrate the devices by which these objects are attained in the accompanying drawings, wherein—

Figure 1 is a side view in elevation of a sleigh containing my invention with the wheels in position for supporting the sleigh. Fig. 2 is a rear end view of the same. Fig. 3 is a vertical longitudinal sectional view of a portion of Fig. 1, showing the position of the wheel-supporting devices when the sleigh is resting on its runners. Fig. 4 is the same with the wheels in position for supporting the sleigh.

a represents the runners of an ordinary hand-sleigh.

b are the knees, and *c* are the cross-beams.

d is the bottom of the box or platform, supported upon the beams in the ordinary way, 55 and *e* is a cross-piece secured to the under side of the platform *d* at any desirable point, preferably in a position to be nearly beneath the center of gravity of the sleigh.

f f are brackets secured by their upper 60 edges to the under side of the piece *e*, and, extending downwardly, are provided in their lower portions with notches *g*, the front portions *h* of the notches extending below the rear portions *i* thereof, and in the upper portion of each bracket and directly over the notch *g* is arranged a vertical slot *k*.

l is a supporting piece or frame placed between the brackets *f*, and provided on the upper portion of its ends with pivots *m*, projecting into the slots *k*, and is also provided with projections *n*, so located on its ends that when the pivots *m m* are resting in the upper portions of the slots the projections *n* will rest within the notches *g*. 75

o o are portions of the supporting-piece extending below the projections *n*, and between these portions *o o* are journaled the wheels or rollers *p*, the lower portion of the peripheries of the wheels projecting below the runners *a* when the wheels are in the position shown in Figs. 1 and 2.

q is a spring with one end secured to the cross-piece *e* or to the platform, and with its opposite end secured to the supporting-piece 85 *l*, and operates to raise the supporting-piece to retain the pivots *m* in the upper portion of the slot and the projections *n* into engagement with the notches *g*.

r is a lever, with its upper end pivoted to a 90 support *s*, secured to the under side of the cross-piece *e*, and with its lower free end extending downward on the front side of the supporting-piece *l*, and is provided with a curved end portion *t*, with the upper end of the curve 95 beginning just above the supporting-piece, and to the curved end which projects below the piece *l* is secured one end of the cord *u*, which leads upward to one of the handles *v* of the sleigh, where it is secured by its opposite end 100 to a catch-piece *w*. This catch-piece is arranged to slide on a bar *x*, which is secured to the handle *v*, and is provided on its upper end portion with a notch *y*, and the piece *w* is also provided with a projecting catch *z*, 105 which engages with the notch *y* when the

catch-piece is drawn to the upper portion of the bar, and projecting outwardly from the catch-piece is a handle a' , so constructed as to be easily grasped by the fingers for disengaging the catch.

It will be noticed that when the device is in the position shown in Figs. 1 and 2 the wheels will project below the runners and support the sleigh, and the sleigh can then be moved over bare ground or pavement upon the wheels; but when it is desirable to rest the runners upon the snow the sleigh is tilted forward and the catch-piece is grasped by the handle and drawn upwardly, and the cord 10 actuating the lever r to the rear brings the curved portion thereof to bear downwardly upon the supporting-piece l , which disengages the portions n from the notches g , and the cord on being further pulled upward raises 15 the wheels by turning the supporting-piece l upon the pivots m in the slots, and when the wheels are raised to the position shown in Fig. 3 the projection z will be in a position to engage with the notch y , which retains the 20 wheels in this position with the sleigh-runners resting upon the snow, and to place the wheels again in position to carry the sleigh the rear end of the sleigh is raised, and the catch-piece is then drawn upwardly to disengage 25 the catch from the notch y , and then on loosening upon or releasing the catch the gravity of the wheels causes the supporting-piece to turn forward and downward upon its pivots, and the projections n strike the short 30 side of the notch, which being inclined moves the pivots to the lower portion of the slots k , and the spring q then raises the supporting-piece and engages the projections n with the notches g , where they remain until the cord 35 is again pulled to operate the lever r .

This operation of the device enables a person to propel a sleigh either on its runners or upon the wheels, and is especially desirable for use upon sleighs arranged for carrying children, as the sleigh can be loaded within doors upon the bare floor when resting upon the wheels, and the sleigh can then be run over the floor or bare walks till the snow is reached, and then the wheels may be 40 withdrawn and the runners then rest upon the snow in the usual manner. Of course it will be noticed that the form and construction of the brackets and the supporting-piece can be changed to suit sleighs of various 45 forms, and it is not necessary that the supporting-piece which carries the wheels should swing backwardly, as the cord can be attached to a tongue located forward of the sleigh, so as to swing the wheels forwardly, if desired, 50 and the operating-lever can be differently arranged, if desired, and produce the same result, so that I wish it understood that I do not limit my invention entirely to the form and location of the various devices as herein 55 illustrated and described; and therefore

I claim as my invention the following:

1. The combination, with a sleigh, of a supporting-piece having its upper portion pivotally secured to the under side of the sleigh-platform and having wheels or rollers journaled to its lower free end, a catch rigidly secured to the sleigh and engaging with the said supporting-piece for retaining it in a vertical position, and a spring for engaging the supporting-piece with the catch, substantially as set forth. 70

2. The combination, with a sleigh, of a supporting-piece pivotally secured to the under side of the sleigh-platform and capable of a vertical movement in its pivotal supports, the wheels mounted on the lower portion of the said supporting-piece and with the lower portions of their peripheries projecting below the sleigh-runners, the catches rigidly secured to the sleigh and engaging with the supporting-piece when in a vertical position, a spring for moving the supporting-piece upwardly to engage the said catches, and devices for moving the supporting-piece downwardly to disengage the catches, substantially 80 as set forth. 85

3. The combination, with the sleigh, of the brackets secured on opposite sides of and to the under side of the sleigh-platform and with each bracket provided in its upper portion with a vertical slot and on its lower edge with a notch, a supporting-piece between the said brackets, provided with wheels journaled to its lower portion and with pivots projecting from the upper portion of its ends and resting in the said vertical slots and having on the middle portions of its ends projections resting in the said notches in the lower edges of the brackets, and a spring for holding the said projections in engagement with the notches, substantially as set forth. 95

4. The combination, with a sleigh and the brackets f , secured beneath the sleigh-platform and provided with the slots k and the notches g , and the supporting-piece l between the brackets, and having pivots m , resting in the slots k , and the projections n , resting in the notches g , and provided with a spring for holding the projections n in engagement with the said notches, of the lever r , with its upper end pivotally secured to the under side of the sleigh-platform, and provided on its lower free end with a curved portion t , engaging with the said supporting-piece, and devices, substantially as described, for operating the lever to raise the said supporting-piece from a vertical to a horizontal position, substantially as set forth. 110 115

In testimony whereof I affix my signature in presence of two witnesses.

MELVIN L. WILCOX.
